4 Claims. (Cl. 230—45)

Purely axial-flow and purely radial-flow compressors are known. The axial-flow compressor has generally a relatively high efficiency, particularly at relatively high powers. This higher efficiency is particularly obtained in the partial-load region by a suitable adjustment of the stationary blades. On the other hand, axial-flow compressors are, owing to design reasons, less suitable for interstage cooling so that higher pressure ratios require a correspondingly large number of stages. Inverse conditions are obtained with radial-flow compressors. They have generally a relatively lower efficiency, particularly in the partial-load region, because the swirl control required for this purpose requires the incorporation of special stationary blades before the moving blades. On the other hand, interstage cooling can be provided for without special difficulties in radial-flow compressors.

Apart from the use of blades having an axial-flow inlet portion and a radial-flow outlet portion, it has already been proposed to arrange axial-flow blades and radial-flow blades in different forms in a multistage compressor. It has not yet been possible, however, to obtain an optimum utilization of the properties of both types of blades.

For the practical success of such a combined axial- and radial-flow compressor, its performance under different operating conditions is of great importance. Hence, it is an object of the invention to provide a solution in this respect mainly for compressors which in spite of a constant operating speed imparted to the compressor by an electric motor drive are required to have not only a high overall efficiency but also an optimum power consumption at partial loads, at a capacity of, e.g., 70% of the normal full-load capacity.

Hence, the invention utilizes adjustable stationary blades, such as are known per se in axial-flow stages. In known combined axial- and radial-flow compressors, such adjustable stationary blades have been used in all axial-flow stages, and the resulting greater length of the compressor has partly been compensated by the use of at least one radial-flow impeller as the last stage. The invention, however, is based on a recognition which is of special significance for relatively high compression ratios, i.e., for compressors having a large number of stages. This recognition resides in that the desired object can be quite adequately accomplished even when adjustable stationary blades are provided only to a limited extent. Hence, the invention resides in that only a part of the axial-flow stages is provided with adjustable stationary blades and at least one axial-flow stage having non-adjustable stationary blades is disposed between these adjustable axial-flow stages and the succeeding radial-flow stage or stages.

If a plurality of successive axial-flow stages are to be provided with adjustable stationary blades, it is advantageous to use for this purpose a common adjusting linkage. Intermediate levers of different length may be provided

2

in known manner for an adjustment through different angles. In this connection, a further feature of the invention resides in that the length of the intermediate levers is such that the largest angle of adjustment is obtained in the first stage and the angle of adjustment obtained in each succeeding adjustable stage is somewhat smaller than in the preceding stage in such a manner that a zero pressure rise is obtained in each of these stages when they are all completely shut off.

The above-mentioned features of the invention may be used with different arrangements of the axial-flow and radial-flow stages. For instance, a plurality of axial-flow stages serving as a low-pressure section and a plurality of radial-flow stages serving as a succeeding high-pressure section may be arranged on a common shaft, and a cooler may be interposed in known manner between any two adjacent radial-flow stages. Alternatively, two stage groups, each of which comprises preferably a plurality of axial-flow stages and a succeeding radial-flow stage, may be arranged for mutually opposed directions of axial flow in such a manner that the inlet axial-flow stages of the two groups lie on the outside beside the shaft bearings and their outlet radial-flow stages lie on the inside one beside the other. A cooler is suitably interposed between the two combined axial- and radial-flow stage groups.

In conjunction with the last-mentioned type, particularly high compression ratios (up to 10 or higher) may be achieved if the second combined axial- and radial-flow stage group is succeeded by a second cooler followed by a single radial-flow stage, which is preferably floatingly mounted on the shaft end opposite to the drive motor.

Several illustrative embodiments of the invention are shown partly diagrammatically on the drawings.

FIG. 1 shows a compressor which comprises four low-pressure, axial-flow stages succeeded by three high-pressure, radial-flow stages.

FIG. 2 shows a compressor which comprises adjustable axial-flow stages 8-11 and a non-adjustable axial-flow stage 16.

The compressor shown in FIG. 3 has two stage groups, the first of which consists of five series-connected axial-flow stages and a succeeding radial-flow stage, whereas the second stage group has four axial-flow stages and a succeeding radial-flow stage.

FIG. 4 shows a modification of FIG. 3 and includes an additional radial-flow stage, which is floatingly mounted on one end of the shaft outside the shaft bearing and succeeds the second stage group.

FIG. 5 is a graph showing an operating characteristic curve *a* for the pressure rise in percent of a centrifugal compressor plotted against the volumetric intake rate.

FIG. 6 shows a comparison between the power consumption in percent of a cooled radial-flow compressor having swirl-controlled first stages and of an axial- and radial-flow compressor having adjustable stationary blades in the axial-flow section, in the same range of about 70-110% of the normal volumetric intake rate at full load (100%).

The compressor shown in FIG. 1 comprises a low-pressure section 1 comprising four axial-flow stages, and a succeeding high-pressure part 2 consisting of three radial-flow stages. All axial-flow stages and radial-flow stages are mounted in a common housing 3 and are carried by a common shaft 4 between two supporting bearings 5, 6 of this shaft. The last radial-flow stage has an inlet in

a direction which is opposite to the two other radial-flow stages and the axial-flow stages so that the axial thrust is at least partly compensated. More radial-flow stages may be reversed in this way, except for the first one, the inlet of which is suitably directly opposite to the outlet of the last axial-flow stage, for flow-dynamical reasons.

An interstage cooler is arranged between every two adjacent radial-flow stages. In the present case, two interstage coolers are provided, which are suitably symmetrical arranged on both sides of the compressor and for this reason are not apparent from the longitudinal sectional view which is shown.

The stationary blades of the axial stages are adjustable according to the invention with the aid of a common adjusting linkage 7. Details of such an adjusting device, which is known per se, are apparent on a larger scale from FIG. 2. A special feature resides in that the intermediate levers 12-15 leading to the stationary blades of the various adjustable axial-flow stages 8-11 have different lengths. The intermediate lever 12 associated with the first axial-flow stage 8 is the shortest. The intermediate lever of each succeeding, adjustable axial-flow stage is somewhat longer than that of the preceding stage. In spite of a joint operation of all adjustable stationary blades, the blades of succeeding stages are adjusted through different angles. The relatively largest angle of adjustment is obtained in the first stage 8 and the relatively smallest angle in the last stage 11. Tests have shown that the different angles of adjustment are suitably selected so that a reduced total pressure rise of all adjustable axial-flow stages is divided so as to obtain progressively increasing stage pressure rises, and that for a zero overall pressure rise the pressure rise of each stage is also zero.

Such an adjusting device enables the respective axial-flow stages to be entirely or largely shut off in consideration of their different blade lengths so that during partial-load operation the fluid to be compressed can flow substantially without obstruction through these stages with a power consumption which is very small in comparison with that of the swirl control employed with radial-flow stages.

In the example shown in FIG. 2, the adjustable axial-flow stages 8-11 are succeeded by a non-adjustable axial-flow stage 16.

According to FIG. 3, a shaft 19, which is driven by a clutch 18 from a motor 17, carries two stage groups 20, 21 between two shaft bearings 22, 23. One stage group 20 comprises five series-connected axial-flow stages and a succeeding radial-flow stage. The other stage group 21 comprises four axial-flow stages and a succeeding radial-flow stage. Both stage groups are disposed in such a relation to each other that the inlet axial-flow stages are disposed on the outside beside the shaft bearings and the radial-flow stages are arranged on the inside one beside the other. This results in a considerable compensation of the axial thrust as well as in a relatively low pressure differential at the two outer stuffing-boxes beside the shaft bearings and on the inner stuffing-box between the two radial stages so that these stuffing boxes can easily be sealed.

A cooler 24 is arranged between the two stage groups 20, 21. This cooler may be attached to the compressor housing, not shown, or may be separate from this housing. As a result of the effective interstage cooling, the volume of the pre-compressed fluid is considerably reduced from the outlet of the radial stage of the first stage group 20 to the inlet of the first axial-flow stage of the second stage group 21.

In FIG. 4, like reference characters designate parts which are similar to those used in FIG. 3. FIG. 4 shows an additional radial-flow stage 25, which is floatingly mounted on one end portion of the shaft 19 outside the

shaft bearing 23 and succeeds the second stage group 21. A second cooler 26 is arranged between the outlet radial-flow stage of the second stage group 21 and the additional radial-flow stage 25. While retaining all other advantages of a compressor according to the invention, this embodiment enables an even higher overall compression ratio.

In the embodiments shown in FIGS. 3 and 4, the axial-flow stages are provided at least in part with adjustable stationary blades for a good adaptation to changing operating conditions.

In FIG. 5, curve *a* represents the operating characteristic curve of a centrifugal compressor. The pressure rise in percent is plotted against the volumetric intake rate.

FIG. 6 represents the power consumption in percent with the range of about 70-110% of the normal volumetric intake rate at full load (100%) for a cooled radial-flow compressor which has swirl-controlled first stages and an axial- and radial-flow compressor having adjustable stationary blades in the axial-flow section. These curves *b* (for the pure axial-flow compressor) and *c* (for the combined axial- and radial-flow compressor) have been measured and computed for two compressors which have the same final pressure and indicate that the compressor according to the invention has a lower power consumption throughout the range which is represented. This difference is particularly high in the partial-load region.

What we claim is:

1. A multi-stage centrifugal compressor comprising, in combination, a common drive shaft extending between a pair of axially spaced bearings; two serially connected multi-stage sections supported on said common drive shaft between said bearings; a common housing enclosing both multi-stage sections between said bearings; each multi-stage section comprising plural axial flow fluid inlet stages and at least one radial flow fluid outlet stage, the axial flow stages being at the axially outer end of each section and the radial flow stages being disposed axially between the two sets of axial flow stages; the fluid flowing serially through the two sections in respective opposed axial directions; at least one axial stage of each section having adjustable guide vanes; adjusting means operable to adjust said guide vanes; and a cooler connected to the outlet of at least one radial stage.

2. A multi-stage centrifugal compressor, as claimed in claim 1, in which plural axial stages of each section have said adjustable guide vanes; said adjusting means including respective crank arms each connected to the guide vanes of a respective axial stage; a common operator connected to the free ends of said crank arms to simultaneously pivot all of said crank arms; said crank arms having different lengths with the lengths of the crank arms varying in a manner such that the adjustment angle for the first axial stage has the largest value, with the adjustment angle for each succeeding axial stage being progressively smaller.

3. A multi-stage centrifugal compressor, as claimed in claim 2, in which the unequal adjustment angles for the guide vanes of respective axial stages have values such that, with zero pressure increase for all of the axial stages of the respective section, the pressure increase for each individual axial stage is equal to zero.

4. A multi-stage centrifugal compressor, as claimed in claim 1, including an individual radial flow stage supported on said common drive shaft and arranged, in the direction of fluid flow through said compressor, downstream of said two serially connected multi-stage sections; and a cooler connected between the outlet of the downstream one of the two serially connected multi-stage sections and the inlet of said individual radial stage.
